INVENTOR.

STANLEY W. NICHOLSON

BY *Stanley W. Nicholson*

ATTORNEY.

UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW REGULATOR.

Application filed March 8, 1926. Serial No. 93,251.

The invention relates to window regulators and is designed particularly for use in raising and lowering the windows of a railway car. The invention has for some 5 of its objects the provision of a window regulator which may be installed in a railway car without changing the construction of the latter; the provision of a window regulator having a crank which is so located 10 that it does not interfere with the seating arrangement but is readily accessible for operation; the provision of a dual window regulator having lifter arms for independently raising and lowering the inner and 15 outer windows of a railway car; and the provision of means for raising and lowering a window screen respectively upon lowering and raising a window. With these as well as other objects in view, the invention resides 20 in the novel features of construction and combinations and arrangements of parts as more fully hereinafter set forth.

In the drawings:

Figure 1 is an interior side elevation of a 25 portion of a railway car having applied thereto a window regulator embodying my invention;

Figure 2 is a similar view, enlarged and partly broken away, to more clearly illustrate the invention;

Figures 3 and 4 are cross sections respectively on the lines 3—3 and 4—4 of Figure 1;

Figures 5 and 6 are cross sections respectively on the lines 5—5 and 6—6 of Figure 2;

Figure 7 is a diagrammatic vertical sectional elevation showing the manner of operating a window screen.

In general, and as shown particularly in Figure 1, a railway car such as a Pullman car has pairs of adjacent window openings with mirror panels 1 between the adjacent openings of the pairs and light panels 2 of 45 considerably greater width than the mirror panels between the pairs of window openings. The widths of these light panels are sufficient to take care of the combined depths of the backs of the oppositely facing seats

50 3. The light panels 2 each carry a pair of laterally spaced electric lights 4 and 5 which are located above the backs of the seats and may be separated by suitable partitions used in making up the berths. 6 are metallic

channel-shaped uprights opening toward each other and arranged in pairs, alternate pairs being located between the pairs of window openings and the adjacent window openings of the pairs. 7 is the outer panel of the railway car and 8 is a panel above the light panels 2 and forming therewith the inner panel of the railway car. These uprights with the inner and outer car panels form chambers above the window openings for receiving the windows when raised and also form vertical chambers between the pairs of window openings of considerable cross sectional area which with the chambers above the openings house the regulators for operating the windows adjacent to and on opposite sides of the light panels. These window regulators, as shown, comprise lifter arms and mechanisms for actuating the arms.

Each window regulator is in the nature 75 of a dual window regulator and has the lifter arms 9 and 10 which extend within the chambers above and at one side of a window opening laterally adjacent a light panel. The arms are suitably connected to the inner and outer windows 11 and 12, respectively, as by means of the angularly grooved pins 13 upon the outer ends of the arms and the retainers 14 secured to the upper edges of the windows. The points of engagement 80 between the pins and retainers are substantially in line with the vertical median planes of the windows. The arms 9 and 10 extend through the openings 15 located in the web of the upright 6 and are pivotally mounted upon the mounting plate 16 which is secured to the web and has the hub 18, at the opposite ends of which the arms are mounted. 85 17 is the pin extending through the arms and hub for pivotally connecting the same. The distances between the inner ends of the arms and their pivots are less than one-half 90 the width of the chamber laterally adjacent to the window opening so that the arms of one dual window regulator can not interfere 95 with the arms of the other dual window regulator making use of the same chamber between the window openings.

For swinging the lifter arms to raise and lower the windows which are connected thereto, I have provided the racks 19 and 20 which extend upwardly within the chamber at the side of the window opening and are

pivotedly connected at their upper ends to the inner ends of the lifter arms 9 and 10, respectively. The teeth of these racks face toward each other and respectively mesh 5 with the lower and upper pinions 21 and 22 on opposite sides of the plane extending through and parallel with the axes of these pinions. The racks 19 and 20 are held in mesh with their pinions 21 and 22, respectively, by suitable means such as the lower and upper rolls 23 and 24, respectively, which engage the backs of the racks. The pinions and the racks are so arranged that during the swinging of the lifter arms and 10 also the more limited swinging of the racks, neither rack can come into engagement with the pinion for driving the other rack.

The rolls and the means for rotating the pinions are carried by a mounting which is 20 so positioned that the cranks of the pinion actuating means are preferably located below the electric lights upon the light panels 2. As shown, the mounting comprises the vertically extending channel 25 having foot 25 flanges 26 extending toward each other and rigidly secured to the outer car panel 7 by suitable means such as the bolts 27 and nuts 28. 29 is a second vertically extending channel which is located within the channel 25 and has its web laterally spaced from the web of the last-mentioned channel. The rolls 23 and 24 have reduced ends which are journaled in these laterally spaced webs of the channels. The pinions 21 and 22 are interchangeable and as shown are elongated and have outer reduced ends journaled in the web of the channel 29 and inner ends extending through and journaled upon the web of the channel 25. 31 are drive shafts suitably 30 connected to the pinions by irreversible drive mechanism located within the cups 30 which are rigidly secured to the inner sides of the webs of the channels 25. The inner ends of the pinions and the outer ends of the 40 shafts are preferably journaled in these cups. The shafts 31 extend freely through the light panels 2 below the electric lights carried by these panels and have fixedly secured to their inner ends the cranks 32.

50 The light panels 2 are provided with the inwardly extending embossed portions 2' through which the shafts 31 extend. These embossed portions form escutcheons against the inner faces of which the cranks abut. Furthermore, these embossed portions form 55 bearing for the hubs 32' of the cranks and consequently rotatably support the inner ends of the shafts 31.

For the purpose of guiding the racks, the 60 rolls 23 and 24 are preferably provided with annular grooves 33 in which the backs of the racks engage. These rolls are also preferably made to be interchangeable.

65 For the purpose of counterbalancing the weights of the windows, I have provided the

tension coil springs 34, which are connected to the lower ends of the racks 19 and 20 and to the frame of the railway car at the lower end of the chamber between the pairs of window openings.

The windows 11 and 12 are of the sashless type to accommodate the lifter arms and the window screen 35, which is adapted to extend between these windows. 36 are vertical guideways formed of fibrous material such as felt and having parallel grooves cut therein for engagement with the windows and screen. These guideways are secured against the webs of the uprights 6 and form weather seals between the edges of the windows and the uprights. 37 is a yieldable abutment preferably formed of rubber mounted upon the sill 38 at the bottom of each window opening. This abutment is secured to the sill by means of the stool 39 which has the recess 40 for receiving the bead 41 upon the inner edge of the abutment. The abutment has the concavities 42 in its upper face providing the shoulders 43 for engagement with the windows and screen, so that the abutment is adapted to form a weather seal between the lower edges of the windows and the sill.

The screen is raised and lowered upon movement of one of the windows, which in the present instance is the inner window 11. Furthermore, the screen is normally concealed in the chamber above the window opening when the inner window is in its lowermost position. The connection between the screen and the inner windows comprises cables 44 located to lie within the grooves formed in the guideways 36, each cable having one end secured preferably to the inner panel above the opening and the other end secured to the upper edge of the screen, intermediate portions of the cable passing over the pulley 45 upon the upper edge of the inner window and also the pulley 46 preferably secured to the inner panel of the car. With this arrangement, the screen has twice the travel of the inner window so that when the latter is raised to its full open position, at which time its lower edge occupies a position vertically midway of the opening, the screen is completely lowered to rest upon the yieldable abutment 37.

What I claim as my invention is:—

1. The combination with a vehicle having a window opening and chambers above and at one side of the opening and a window for the opening movable into the chamber above the opening, of a regulator for operating said windows having portions within said chambers.

2. The combination with a vehicle having a window opening and chambers above and at one side of the opening and a window for the opening movable into the chamber above the opening, of a regulator for oper-

ating said window having portions within said chambers, and a crank located at one side of the opening.

3. The combination with a vehicle having window openings, a chamber between the openings, chambers above the openings and windows for the openings, of a window regulator for each window having portions within the chambers above the openings and other portions within the chamber between the openings.

4. The combination with a vehicle having a pair of window openings, a chamber between the openings, chambers above the openings and windows for the openings, of window regulators each having a lifter arm extending within a chamber above an opening and the chamber between the openings, and means within the chamber between the openings for actuating said arm.

5. The combination with a vehicle having a pair of window openings, a chamber between the openings, chambers above the openings and windows for the openings, of a window regulator for each window having a lifter arm extending within a chamber above an opening and the chamber between the openings, and means for actuating said arm including a member in the chamber between the openings, and a crank located between the openings.

6. The combination with a vehicle having a window opening and chambers at one end and at one side of the opening and a window for the opening movable into the chamber at one end of the opening, of a regulator for operating said window having a pivotal lifter arm extending within both chambers, a rack extending within the chamber at the side of the opening and connected to said arm, a pinion meshing with said rack and a crank for said pinion.

7. The combination with a vehicle having a window opening and chambers above and at one side of the opening, and laterally spaced windows for the opening, of a dual regulator for operating the windows including members extending within both chambers, and means within the chamber at the side of the opening for operating said members.

8. The combination with a vehicle having a window opening and chambers above and at one side of the opening and laterally spaced windows for the opening, of a dual regulator for operating the windows including members extending within both chambers, a support common to both of said members, and means within the chamber at the side of the opening for actuating said members.

9. The combination with a vehicle having a window opening and chambers above and at one side of the opening and laterally spaced windows for the openings, of a dual

regulator for operating said windows having lifter arms extending within both chambers and operatively connected to said windows, racks extending within the chamber at the side of the opening, pinions meshing with said racks and cranks for driving said pinions, said cranks being located at one side of the opening.

10. The combination with a vehicle having a window opening, and chambers above and at one side of the opening and a window for the opening, of uprights separating the chambers and a window regulator for operating said window having an arm mounted upon one of said uprights.

11. The combination with a vehicle having a window opening and chambers above and at one side of the opening and a window for the opening, of a window regulator including a lifter arm extending within both chambers and operatively connected to a window, means within the chamber at the side of the opening for actuating said lifter arm, and means also in said last mentioned chamber for counterbalancing the window.

12. The combination with a vehicle having a window opening and chambers above and at one side of the opening and a window for the opening movable into the chamber above the opening, of a regulator for operating said window having a pivotal lifter arm extending within both chambers and operatively connected to said window, means extending within the chamber at the side of the opening for actuating said lifter arm and a coil spring also located within said last mentioned chamber and connected to said actuating means for counterbalancing the weight of said window.

13. The combination with a vehicle having a window opening, a window for the opening and a panel at one side of the opening, of a regulator for operating said window having a member operatively connected to said window and actuating means behind said panel for said member and a crank connected to said actuating means and located at the inner side of said panel.

14. The combination with a vehicle having window openings and a panel between the openings of a width to accommodate the combined thickness of the backs of two oppositely facing seats and windows for the openings, of window regulators for operating said windows and cranks for said window regulators located above the seats at the inner side of said panel.

15. The combination with a vehicle having a window opening and chambers above and at one side of the opening and a window for the opening, of a window regulator for operating said window having a member extending within both chambers, a rack operatively connected to said member and extending within the chamber at the side of the

opening, a pinion meshing with said rack, a roll for holding said rack in mesh with said pinion, and means within the chamber at the side of the opening and carrying said pinion and roll, said means including cooperating channels having laterally spaced webs.

16. The combination with a vehicle having a window opening and a panel at one side of the opening and a window for the opening, of a regulator for operating said window and a crank for said regulator located at the inner side of said panel, said panel having an embossed portion adjacent to said crank and forming the escutcheon.

17. The combination with a vehicle having a window opening, a panel at one side of the opening and a window for the opening, of a lifter arm pivotally connected to said window, a rack operatively connected to said lifter arm, a pinion meshing with said rack and means for driving said pinion, including a shaft and a crank upon said shaft and located at one side of said panel, said panel having an embossed portion forming the escutcheon and supporting said shaft.

18. The combination with a vehicle having a window opening and a window for the opening, of a screen adapted to close the opening and a window regulator for actuating said window and screen operable from a position at one side of said window, said screen being movable with the window and in a direction opposite to that taken by the window.

19. The combination with a vehicle having

a window opening and a movable window for the opening, of a screen for the opening connected to the window and movable in a direction opposite to that taken by the window and a window regulator for actuating said window and screen operable from a position at one side of said window.

20. The combination with a vehicle having an opening and laterally spaced windows for the opening, of a screen adapted to extend between said windows and a window regulator for actuating said windows and screen operable from a position at one side of said window.

21. The combination with a vehicle having a window opening, and chambers above and at one side of the opening and a window for the opening, of an upright separating the chambers having an opening therein and a window regulator for operating said window having an arm extending through said opening and pivotally mounted therein.

22. The combination with a vehicle having a window opening, and chambers above and at one side of the opening, and a window for the opening, of an upright separating the chambers having an opening therein, a bracket secured to said upright having a hub extending through said opening and a window regulator for operating said window having an arm pivotally mounted on said hub.

In testimony whereof I affix my signature.

STANLEY W. NICHOLSON.
